UNITED STATES PATENT OFFICE.

VERNON E. LA MASTER, OF BEARDSTOWN, ILLINOIS, ASSIGNOR OF ONE-HALF TO
THOMAS J. SMEDLEY, OF FREDERICK, ILLINOIS.

AUTOMOBILE-RADIATOR.

1,346,216.

Specification of Letters Patent. Patented July 13, 1920.

Application filed October 16, 1917. Serial No. 196,929.

To all whom it may concern:

Be it known that I, VERNON E. LA MASTER, a citizen of the United States, residing at Beardstown, in the county of Cass, State 5 of Illinois, have invented certain new and useful Improvements in Automobile-Radiators; and I do hereby declare the following to be a full, clear, and exact description of the invention such as will enable others 10 skilled in the art to which it appertains to make and use the same.

This invention relates to automobile radiators.

The object of the invention is to provide 15 a simple arrangement for maintaining heat in a water circulating system of an automobile engine, so that the usual delay incident upon cranking a cold automobile engine will be avoided. In carrying out the 20 invention I have provided a heating element which is fed from the fuel supply of the automobile, and is so arranged that it may be kept in operation during that period when an automobile is standing still, 25 either in the street or in a garage.

With the above objects in view, and such others relating to the details of construction, as may hereinafter appear, my invention will now be fully set forth and described, reference being had to the accompanying drawings.

In the drawings:—

Figure 1 is a section through an automobile radiator showing my invention applied 30 thereto,

Fig. 2 is a section through the system,

Fig. 3 is a detail section of the burner element,

Fig. 4 is a transverse section through the 40 radiator.

Referring more particularly to the drawings, 1 represents the usual automobile radiator which consists of the upper manifold or chamber 2 and the lower chamber or 45 manifold 3, the latter being connected by means of the usual spaced water tubes 4. Extending vertically through the bank of water tubes 4 is a conduit 5. On lines which coincide with substantially the central portions of the chambers 2 and 3, the conduit 5 branches in both directions in the arms 6 and 7. The extremities of the arms 6 and 7, near the corners of the radiator, are connected by means of the vertical conduit 50 components 8, so that two courses of cir-

culation are provided, namely, one through the conduit 5 and the other through the arms and the vertical components. In other words, one portion of the heated air will travel direct through the main conduit 5, 50 and the other portion will divide, the parts traveling through the longer course including the arms and the side components. It is believed the heat passed direct through the main conduit will be more intense and 55 will move more rapidly than that which passes through the components, and this is desirable because it will heat the water at the transverse center of the radiator to a higher degree than at its sides and therefore will set up a circulation in the water 60 as will be clearly understood. The upper end of the conduit 5 vents through the top of the radiator, and the lower end thereof passes through the bottom of the radiator 65 and terminates in a hood 9.

The hood 9 lies inside of a heater casing 10 within which is located a gasoline generator burner 11 preferably of the retort type, which may be kept in a burning state by 70 means of a comparatively small quantity of gasoline which is fed thereto through a pipe 12 which comes from the fuel supply tank not shown. The generator burner 11 is disposed directly below the hood 9, 75 so that all of the heat therefrom will pass into the lower end of the conduit 5, and will be distributed in the manner above defined. The casing may have a door to give access 80 to the heater, and the casing or the door 85 may have openings to admit air.

In order to restrict and hence to retard the flow of heat through the arms 7, baffles 13 are disposed at their points of union with the main conduit 5 as best seen in 90 Fig. 2. As therein illustrated, these baffles are small plates converging upward toward the axis of the main conduit.

It will be apparent from the foregoing description that I have provided a simple 100 and effective means for maintaining a degree of heat in the water circulating system of an automobile, and that by the use of a gasoline generator burner, the heat may be maintained for a long period at a slight expenditure of fuel. In fact, the device may be kept burning throughout the 105 night in a garage, so as to prevent the freezing of the water system with consequent damage to the machine.

2
What I claim as my invention is:—

1. The combination with an automobile radiator; of a subjacent casing adapted to contain a heating unit, a main conduit leading from a point above said unit vertically through the center of the radiator and open at its top, and other conduits branched from the first and extending in tortuous courses upward through the radiator near 10 its sides and top and united near the latter with said main conduit, as and for the purpose described.

2. The combination with an automobile radiator, of a casing for attachment to the 15 bottom of the radiator and adapted to contain a heating unit, a hood above said unit, a main conduit leading from the hood

straight upward through the radiator and open at its top, arms branched from the conduit and extending outward in the radiator near its bottom, thence upward in vertical components, and thence inward in other arms near the top of the radiator and united with said conduit, and baffles at the juncture of the lower arms and conduit leaving the 25 axis of the latter open but restricting the flow of heat through said arms, as described.

In testimony whereof, I affix my signature in the presence of two witnesses.

VERNON E. LA MASTER.
